US00D983772S

(12) **United States Design Patent** (10) **Patent No.:** **US D983,772 S**
Brunner et al. (45) **Date of Patent:** ** *Apr. 18, 2023

(54) **EARPIECE**

(71) Applicant: **Apple Inc.**, Cupertino, CA (US)

(72) Inventors: **Robert Brunner**, Glen Ellen, CA (US);
Christopher Kuh, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/825,906**

(22) Filed: **Feb. 7, 2022**

(58) **Field of Classification Search**

USPC D14/223, 205; D24/174; 128/864-866;
381/380-381, 322, 328
CPC H04R 1/10; H04R 25/00; H04R 25/02;
H04R 1/1016; H04R 1/1066; H04R 5/033; H04R 5/035; H04R 1/105; H04R 1/1008; H04R 1/1091

See application file for complete search history.

Primary Examiner — Paula Allen Greene

(74) *Attorney, Agent, or Firm* — Sterne, Kessler, Goldstein & Fox P.L.L.C.

(57) **CLAIM**

The ornamental design for an earpiece, as shown and described.

DESCRIPTION

FIG. 1 is a top rear perspective view of an earpiece showing the claimed design;

FIG. 2 is a front view thereof;

FIG. 3 is a rear view thereof;

FIG. 4 is a side perspective view thereof;

FIG. 5 is a top view thereof; and,

FIG. 6 is a bottom view thereof.

The broken lines in the figures show portions of the earpiece or environment that form no part of the claimed design.

1 Claim, 1 Drawing Sheet
